CONVERTIBLE SHIPPING CONTAINER

Hector Price Hughes, New London, Conn., assignor to Robert Gair Company, Inc., New York, N. Y., a corporation of Delaware

Application October 17, 1935, Serial No. 45,401

6 Claims. (Cl. 206—44)

The present invention relates to an improved form of collapsible shipping container, made of such paper board as fibre or corrugated board of, preferably heavy gauge.

One important improvement herein relates to providing for a double-duty container, in which manufactured goods may be packed and shipped, in sealed condition within the container, and then the distributor can break the gummed seal, rearrange the broken, open end closing flaps to provide a sunken, keyed tray-like support, for displaying some of the contents thereof, for sale or self-service. Thus the container has two functions, and is not immediately thrown away, but is used as a display stand until all of its contents have been disposed of.

The foregoing, and other features of advantage will be apprehended as the herein description proceeds, and it will be obvious that modifications may be made in the structure herein without departing from the spirit hereof, or the scope of the appended claims.

In the drawings,

Figs. 1 to 6 inclusive are perspective views of the convertible closure end of the container, Fig. 1 being in sealed form, Figs. 5 and 6 being in fragmentary form, showing in the successive steps of conversion into a goods display supporting tray;

Fig. 7 is a plan view of the key-lock panel;

Fig. 8 is an end view of Fig. 7;

Fig. 9 is a plan view of the converted tray end of the container with the key-lock panel in position;

Fig. 10 is a plan view of a scored advertising panel;

Fig. 11 is a side view of the panel of Fig. 10, bent on the score line into display position; and

Fig. 12 is an enlarged sectional view taken on line 12—12, Fig. 9, looking in the direction of the arrows.

This container is easily made in automatic machines, and is shipped flat or knocked down, in bundles, to the consumer, and is readily erected, filled and sealed.

The container, generally denoted by 1, all figures, comprises the customary four body forming panels A, B, C and D, Fig. 1, the top and bottom ends, F and E respectively, being closed by hinged end closing flaps of customary construction, one flap being defined from each panel and bent to overlap into a closing end assembly, well known to this art.

The top closing end, however, is so constructed that it may be converted into a, preferably re-

cessed, tray and goods supporting and display means of a rigid nature.

The top end closing flaps are shown in Fig. 1 as being closed down and sealed, the outer flaps 2 and 3, being held at their meeting edges 4 by a gummed paper sealing strip, Fig. 1, said strip being indicated by the dot and dash lines 5.

This strip is well known in this art, and to open the container an edged tool is drawn longitudinally of the strip between the ends 4, and flaps 2 and 3, are then pulled up as indicated in Fig. 2. This exposes inner flaps 5 and 6, which may also be opened up and some of the contained goods removed from the container.

After the desired display quantity of goods have been removed, the key-lock panel 8, Fig. 7, and the advertising display panel 13—14, Fig. 10, also carried in the container are also removed, and the open top end flaps 2, 3, 5 and 6 of the container may then be converted into a rectangular recessed platform supporting ledge, upon which a goods supporting platform may be placed to form goods display supporting panels and advertising display means.

As will be noted in Figs. 2 to 6 inclusive, each end flap is traversed by a longitudinal score line, to form auxiliary ledge forming extensions X, this indice being common to all of the ledge forming auxiliaries. Flap 2, which is scored at d to form a hinge line with its body panel B, Fig. 2, is traversed by an unbroken score line c, flap 3 hinged at a to form a hinge line is traversed by an unbroken score line b, flap 5 is traversed by an unbroken score line g, and flap 6 is traversed by an unbroken score line e, being hinged at score line f.

When the flaps are in closed sealing position as in Fig. 1, the score lines c, b, g and e are unbroken and in this condition close the container end.

After the desired articles have been removed from the container, flap 5 is bent inwardly on its hinge score h, as in Fig. 3, until it contacts with the inner face of body panel C, and the auxiliary ledge member X is bent outwardly on score line g at right angles thereto, Fig. 3. Then the next successive closing flap 2 is bent inwardly in the same manner, and with the end of its ledge auxiliary X overlying the associated end of auxiliary ledge member 5x, as shown in Figs. 4, 5 and 6. Then, as in Fig. 4 closing flap 6 is similarly bent in with its ledge X overlapping on its end with the end of associate ledge auxiliary 2x, and finally, flap 3 is similarly inwardly bent with its ledge auxiliary at right angles thereto, 55

the ends of the latter overlapping both of its adjacent, associate ledge auxiliaries $5x$ and $6x$, as disclosed in Fig. 6.

Thus, as in Fig. 6, ledges $2x$, $6x$ and $3x$ are overlaid at one of their ends by their next successive ledge members in the order above named. But ledge $5x$ is overlaid at its ends by the ends of its associate ledge members $2x$ and $3x$, and thus becomes the key member for locking all of the 10 ledge members in horizontal position under load. As disclosed in Fig. 6, the ledge members are only frictionally held, and now require to be locked in operative ledge forming position.

To this latter end, the key-lock panel, shown 15 in Figs. 7 and 8 comprises a flat blank 8 of paper board, preferably of the same gauge and strength of the board used in the container. The same blank 8 has two slots $9-9$ cut therein, at one edge thereof, and parallel to one another. These 20 slots are of sufficient depth and width to permit the entry thereof of the key ledge $5x$, from its front edge 7 . The slots define, between them three extensions 10 , 11 and 12 , the outer, extensions $10-12$ being of like dimensions and of approximately the same width as the ledges $2x$ and $3x$.

The middle extension 11 of panel 8 is of slightly lesser width than the space between the opposed ledges $3x$ and $2x$, and thus the front of the 30 extension 11 may be entered under ledge $5x$, while the extensions $10-12$ are kept on the top of ledges $3x$ and $2x$, and then the panel is pushed completely home, the slots $9-9$ permitting the entry of the ledges $2x$, $3x$ and $5x$, as the panel 35 8 is moved in the direction of the arrow 11 , Fig. 12, the three extensions thus oppositely clamping and locking ledge $5x$ to the two superposed ledges $3x$ and $2x$, these latter, in turn, locking all of the other interconnected ledges X . The panel 40 8 also forms a false platform as it rests upon all of the ledge corners, as in Figs. 9 and 12.

When in use as a display container an advertising display panel, Figs. 10 and 11 is provided, the panel being divided by score line i , Fig. 10, 45 thus defining an advertising section 13 and a base section 14 , when section 14 is bent at right angles to section 13 , as in Figs. 11 and 12, wherein, in the latter figure, the use of the display panel is shown in diagrammatic form.

With the display panel arranged as in Fig. 12, 50 goods may be placed on base section 14 , thus to weight the panel, which further, has the added function of strengthening the platform portion of the tray forming panel 8 , against its superimposed display load.

As will be noted from the foregoing description, this container is sealed in the usual manner, and thereafter, when set up as a display stand, the over folding of the flaps 2 , 3 , 5 and 6 , to form 55 the walls of the recessed display portion leave the edges of the display device at the hinge scores a , h , d and f with smooth edges, there being no raw or cut edges exposed, thus enhancing the appearance of the stand.

As the displayed goods are disposed of, the contained goods are readily accessible, as the advertising and lock panels are easily removed and the stored goods as required removed from the container, in desired quantities.

Having thus described the invention, what is claimed is:

1. A display container made from rigid sheet material comprising a body having four walls and four top end hinged flaps, there being one 75 flap on each wall, each flap having a portion

turned inwardly and engaging the inner face of the associated wall; each portion having an extension, there being score lines between the said portions and their extensions, said extensions being turned into positions at right angles to said portions so as to provide a continuous inner ledge; said extensions including an under supporting member; and a goods supporting panel having its outer margins substantially resting on said ledge, said panel having in one of its margins a pair of slots which provide a medial end portion said latter portion being disposed below said under member.

2. In combination with a container comprising four vertical walls each having integral therewith and disposed below the top thereof within the carton a horizontal member, said members having their ends overlapped in substantial alternate relation so as to provide a ledge, one member being lowermost; a rectangular panel forming a platform and locking said members; said platform having a medial portion of one of its straight margins disposed below said lowermost member, the corner portions of said margin being seated above the ends of said lowermost member, the other three straight margins of the platform being disposed above the other three members of the ledge and seated thereon.

3. A container comprising four coacting vertical walls having top end hinged flaps in which 30 are unbroken scores defining on their opposite sides base portions and flap extensions, said flaps forming a horizontal closure flush with the ends of said walls; whereby when the closure is opened the flaps may be turned into the open end of the 35 container and broken on said scores so that the extensions may then form a sunken ledge at right angles to the base portions.

4. A convertible shipping container made of rigid paperboard comprising four coacting side 40 walls having a bottom and hinged top end flaps in which are bendable lines defining on their opposite sides base flap portions and extensions, said flaps forming a closure flush with the end parts of the walls in the shipping position; whereby when the closure is opened the flaps may be hingedly turned into the open end of the container, so as to engage the base portions against the inner faces of the walls thereat, the flaps being turned on said lines so that the extensions 45 may form a sunken ledge at right angles to said base portions.

5. A combination shipping case and dispensing stand made of stiff paper board comprising four walls having a bottom and a top including 55 opposed single under hinged flaps and opposed single outer hinged flaps having meeting edges and forming a closure level with the ends of the walls in the shipping case position; said flaps having therein weakening score lines which define base portions and flap extensions, whereby after 60 the closure is opened the flaps may be swung into the open end of the case so as to engage the base portions against the inner faces of the walls thereat, said flaps being then bent on said lines, the extensions being turned to form a horizontal ledge, the ledge members being projected uniformly partly towards the center whereby to provide a reduced central dispensing opening.

6. A combination container and display stand 70 comprising a body including four walls having a bottom and top end hinged flaps forming a closure level with the ends of the walls in the container position, said flaps having therein weakening line defining on their opposite sides base por- 75

tions and flap extensions; a rectangular panel for providing a goods supporting platform and having in one of its end margins, on opposite sides of a medial portion thereof, two slots; whereby after the container is opened and some of the contents removed the flaps may be swung into the open end to engage the base portions against the inner faces of the walls thereof, the flaps being then turned on said lines to place the extensions 10 at right angles thereto in the form of a sunken

ledge, the members of the ledge having their ends substantially alternately overlapped, one of said members being lowermost; said panel being then inserted between said base portions, the medial margin portion being disposed below the corresponding part of the lowermost ledge member, the other marginal portions of said panel being disposed above the other parts of said ledge. 5
